UNITED STATES PATENT OFFICE

ELMER G. MARTIN, OF EAST LAMPETER TOWNSHIP, LANCASTER COUNTY, PENNSYLVANIA

DESIGN FOR AN EDUCATIONAL CHART

Application filed December 20, 1932. Serial No. 46,537. Term of patent 7 years.

To all whom it may concern:

Be it known that I, ELMER G. MARTIN, a citizen of the United States, residing in East Lampeter Township, Lancaster County, State of Pennsylvania, have invented a new, original, and ornamental Design for Educational Chart, of which the following is a specification, reference being had to the accompanying drawing, forming part thereof.

The figure is a plan view of the educational chart showing my new design.

I claim:

The ornamental design for an educational chart as shown.

ELMER G. MARTIN.
